UNITED STATES PATENT OFFICE.

FREDERIC W. HILLARD, OF TOTTENVILLE, NEW YORK.

TYPEWRITING MACHINE.

Application filed March 10, 1922. Serial No. 542,663.

To all whom it may concern:

Be it known that I, FREDERIC W. HILLARD, a citizen of the United States of America, and a resident of Tottenville, in the county 5 of Richmond and State of New York, have invented certain new and useful Improvements in Typewriting Machines, of which the following is a specification.

My present invention is particularly directed to improved means for locking up the carriage in its lifted observation position and against endwise movement when free of the escapement, and of key operated means 10 for unlocking the carriage from its lifted position. The present invention is in the nature of an improvement of the machine of my prior Patent No. 1,296,957, patented March 11, 1919 and reissued October 18, 1921, Reissue Number 15,209, although the 15 present invention may also be applied to other machines.

In the drawings herein I show an improved means for holding the carriage against endwise movement when free of the escapement; and also a latch lock for holding the carriage in its lifted position, and a key and means actuated thereby for unlocking the latch lock so that the carriage may be lowered from its lifted position back to 20 its normal writing one.

My invention also contemplates various other detail improvements in connection with the before mentioned objects, which improvements will be more fully pointed out in the accompanying drawings, specification and in the appended claims.

In the accompanying drawings which form a part of the specification, the improvements are fully illustrated. The machine is generally of the type of the machine of my said prior patent, Reissue No. 15,209, excepting for the various modifications and improvements herein shown and described, and it will therefore be understood that I have left out from the various drawings those parts of the machine which are unnecessary to illustrate the invention, thereby making the illustration of the various features of the invention simpler and clearer than they would be were unnecessary parts shown.

Figure 1 is a plan view of the machine with many parts omitted.

Fig. 2 is a side elevation of the carriage parts shown in Fig. 1. This view also 55 shows in dotted lines the position of the carriage when in elevated position and locked in such position.

Fig. 3 is an enlarged detail of the latch lock for holding the carriage, preferably 60 positively in its lifted position, and part of the means for releasing the lock to permit the carriage to be lowered.

Figs. 4, 5, 6, 7 and 8 are detail views of 65 the ball bearing race ways and its truck, together with the latch lock for holding up the lifted carriage, and the truck lock for preventing endwise movement of the lifted carriage.

Fig. 4 is a front view of the race ways 70 and truck.

Fig. 5 is a corresponding rear view.

Fig. 6 is an enlarged view of the left end 75 of Fig. 5, showing the retaining lock members in line with each other, in the position for locking the carriage when lifted and against endwise movement.

Fig. 7 is a detail plan view of part of Fig. 6, showing the position the locking members assume when the carriage has been lifted 80 and locked against endwise movement.

Fig. 8 is a detail side view of the endwise carriage lock, as seen from the end of the machine, the members being shown in full lines in the normal position of the carriage, 85 as illustrated in Fig. 2, and in dotted lines in the locked position in a partially lifted position of the carriage.

Fig. 9 is a modified carriage in plan view, with a modified lock for holding the lifted 90 carriage against endwise movement in an intermediate position of the carriage in its line of travel.

Fig. 10 is a perspective view of the carriage locking finger or nose, one side of 95 which also constitutes the carriage member of the No. 1 endwise lock.

In the drawings, referring particularly to Figs. 1 and 2, the preferred embodiment of my invention comprises a truck 1. Extending forwardly and upwardly from this truck are the brackets 2 which pivotally support 100

the shaft 3, which latter forms a pivotal support for both the inner and outer carriages. The outer carriage, which I will also term the non-shiftable carriage is shown at 4 and this carriage carries rearwardly extending lugs 5 which pivotally engage eccentric bushings 3^a on shaft 3. The inner carriage, also termed the shifting carriage is shown at 6 and this carriage is provided with suitable brackets which support studs 7^a which pivotally engage the forward ends of the shift arms 7. The bearings in the forward ends of these shift arms 7 are closed with caps 8, since it is necessary that the carriage be retained in position when swung upwardly. The opposite (rear) ends of the shift arms 7 are fixed to the ends of the shaft 3, as shown in Fig. 2, being pinned thereon.

20 The inner shifting carriage is adapted to be vertically raised and lowered by any of the well known shift constructions, for example as shown in Fig. 2, in which 9 represents a part of the linkage connecting with the shift key. As this mechanism is the well known mechanism of the Underwood type-writer, as shown in my said prior patent, further description and illustration is believed to be unnecessary. The front end of 25 the outer non-shifting carriage 4, is provided with the usual supporting wheel 10 enclosed in casing 11 and running on front guide rod 13, and there is the usual locking finger 12^a extending forwardly on the carriage beneath the upper front locking bar 12, to lock down the front of the carriage at its proper level while permitting it to run freely in its line of travel on the front guide rail 13. This is the usual construction so 30 that further description is believed unnecessary. The hinge joint at the pivot shaft 3 between the carriage and the truck, permits the carriage to adjust itself to its position on the guide rail 13 and thus prevents friction by undue pressure on the rail or locking bar 12. My truck, in addition to its ball bearing anti-friction race ways advantages, affords a staple anchorage for the carriage when in its lifted position.

35 The truck 1 is mounted upon the machine in the following manner. Two upwardly projecting brackets 14 are mounted on the rear of the machine frame. The upper and lower race ways 15 and 16 are secured to these arms and are preferably adjustable toward and from each other. These race ways are fully described in my said prior Patent Reissue No. 15,209, so that further description, excepting a brief statement of the parts employed, is believed unnecessary.

40 As shown, the upper rail is adjustable toward the lower one by adjusting screws 17. In the race ways I utilize bearing balls 18 (two in each bearing as shown, although more balls may be employed at will) and

the intermediate anti-friction balls (one between each two bearing balls) 19. The balls and their anti-creeping cage 20 move at one-half the speed of the truck and carriage. Upon the front of the truck and adapted to move in unison therewith is a downwardly facing rack 21 which engages a pinion 22 carried by the ball retaining cage 20. Upon the lower race way I mount a second rack 23 which also meshes with the pinion 22.

45 As previously explained the truck 1 has upwardly extending brackets 2 which pivotally support the shaft 3, and the shifting arms 7 are pinned to the ends of this shaft and the usual spring 24 is coiled about the shaft to assist in lifting the inner carriage 6 in its case shifting movements. I also employ a second spring 25 to assist in lifting the shift rail and inner carriage to upper case position, similar to the corresponding spring of my said prior patent. Upon the rear side of the truck there is mounted the tabulator truck plate 26, which serves as a part of the tabulator mechanism; and screwed upon the plate 26 is the margin stop plate 26^a, all as in my said prior patent.

50 The tabulator key 27, key lever 28 and pull bar 29 are the same as in my said prior patent and therefore need not be described in detail. The pull bar is operated by the key through the depression of the key lever 28, and thus rocks the rocker arm 30, which in turn rocks the tabulator pivot bar 31 and thus swings the tabulator rocker frame 32 and tabulator stops 33 forwardly to operate the tabulator. These parts are similar to and operate in the same way as in my said prior patent, and since my tabulator invention is fully described therein further description is deemed unnecessary. It has been here described because such tabulator operating mechanism constitutes a part of my carriage releasing means, the latch lock member 34 being mounted thereon and the swinging of the tabulator rocker frame being utilized to disengage tooth 36 of said member 34 from tooth 52 of the carriage member 41 of the latch lock as illustrated in Fig. 3.

55 At the left hand end of the tabulator rocker frame 32 (looking from the rear of the machine as seen in Fig. 5) I mount one member 34 of the carriage latch lock (see also Fig. 3). This member is fastened to the left end of the tabulator rocker frame 32 by two screws 35 and at its upper end is provided with the rearwardly facing latch lock or locking tooth 36, which constitutes one of the two engaging members of the latch lock. The other engaging member of the latch lock is mounted on the carriage and will now be described. Referring to Figs. 1 and 2, 37 is a back rod which forms a support for the paper margin guide in the machine of my former patent. This rod is

carried on brackets 38 which are rigidly mounted on the side plates of the inner carriage frame 6, beneath the cover plates 39 and are bent inwardly toward each other 5 crosswise of the cover plates, in the usual way and as appears in my said patent and in Figs. 1 and 9 herein. They are then bent upwardly and rearwardly and take in the rod 37 which is squared and screwed (in a set position determined by the squaring and the position of brackets 38) to the brackets by the screws 40, or by a single screw 40 at the right hand end of the rod as seen looking from the front of the machine in Fig. 1, 10 with the left end of the rod merely journaled in its bracket. It will be observed that by bending the inwardly extending portions of the brackets 38 forwardly or rearwardly relatively to the carriage, the rod 37 may be moved forwardly or rearwardly relatively to the carriage and also upwardly or downwardly relatively to the carriage by bending the brackets for that purpose. I employ these means as an adjustment for the carriage member 41 of the latch lock relatively to the tabulator member, to bring the two members into proper relation so that their teeth 36 and 52 will engage properly with each other in the 15 lifted, locked position of the carriage shown in dotted lines in Fig. 2.

The locking member 41 is slidably mounted on the rod 37, and when adjusted to the proper position thereon is clamped to the rod by one or more screws 42 (two screws being shown in Fig. 1) which take into the usual slot 43 on the rod. The rod is milled on parallel sides at the right end (looking from the front of the machine) and is passed 20 through a corresponding perforation with parallel sides as usual, in the right hand bracket 38. This serves to properly locate the slot 43. By bending the upper end of the bracket with the squared perforation angularly the position of the slot will be varied and I employ this means as stated, to adjust tooth 52 to tooth 36 of the latch lock.

The means and method of locking up the lifted carriage by a frictional lock were 25 fully described in my said prior patent and the carriage is also normally locked down in operative writing position by the well known mechanism shown and described in said patent, and shown herein as locking bar 12 and this bar is provided with the releasing slot 44. When the carriage is positioned at a point to the right of the beginning of the line of print, as described in my said prior patent, the locking finger 12^a will be 30 in the releasing slot 44 and the carriage may be lifted. As soon as the carriage begins to be lifted, the rack 46 will be lifted up off from the escapement pinion 47 connected with the escapement wheel 48 and the carriage will be freed from the escapement and,

under the influence of the usual main spring propelling means, tend to advance. But locks 44-56 and 49-50 are provided to resist and overcome this tendency. I will describe these locks more fully hereinafter. 70

As the carriage is being lifted and approaches its fully raised position, the rod 37 engages with the upper beveled cam face 51 on the right hand bracket 14 (i. e. the one shown in Fig. 2). It will be understood 75 that the inner carriage, during the initial lifting movement, is in lower case position, being maintained therein by the influence of gravity. But when the rod 37 engages cam face 51, on a further lifting movement of 80 the carriage and resultant further rearward movement of the rod 37, the rod being forced against cam face 51 lifts the inner carriage faster than the outer carriage is being lifted and hence shifts the inner carriage into upper case position in the outer carriage, as in 85 my said prior patent. Then on the further and final rearward movement, while the teeth 36 and 52 are snapping together to lock the latch lock, the rod 37 passes into 90 notch 51^a and the inner carriage is thus maintained in its upper case position, so that both carriages are locked together while the latch lock remains locked, with the beneficial results described in my said patent, of 95 thus locking the inner carriage rigidly in the outer one. While certain features are therefore similar to my said patent, my present device differs from the said former one in particular which I will now describe. 100

In my prior patent the notch, corresponding to notch 51^a herein, was depended on to hold the carriage frictionally locked in its raised position, against the influence of gravity and other influences to cause it to fall. In my present device I do not depend on a gravity resisting friction lock but instead provide a bolted or hooked lock or a latch lock, or a lock having two engaging members, one of which can be manually withdrawn from the other to unlock the lock. This results that I can employ a key and means operated thereby to withdraw the bolt from the lock or to unlock the latch lock, instead of being forced, as in the prior patent, to exert a strong pull on the carriage to forcibly pull the rod 37 out of the notch 51^a. In my prior patent care had to be exercised not to make the friction lock too strong as otherwise it was difficult to pull 110 the carriage down from locked position; and on the other hand, if the lock were not made strong its reliability against gravity was less and the carriage was apt to accidentally fall. In the present device the notch may or not 115 as preferred, be made strong enough to act, in connection with the bolted lock or latch lock, as an auxiliary frictional lock, so that the carriage will not fall accidentally, even if the operator depress the release key to un- 120 125 130

lock the carriage without at the same time holding the carriage from so falling when unlocked.

While I do not intend to limit myself to any particular type of bolted or hooked lock, I show, for the purposes of illustration and as my preferred form, the latch lock above referred to. The operation of this lock is as follows. In the rearward swinging movement of rod 37 as the carriage is being lifted, the rod first engages cam face 51 and lifts the inner carriage into upper case position, as above described. This compound movement of the inner carriage, relatively to the outer carriage, serves to bring the periphery of lock 41 below tooth 52, in line with and above the upper inclined surface of locking member 34 above tooth 36, so that on a further rearward movement of bar 37 the locking member 34 and tabulator bar 32 will be cammed forward as above described, allowing the tooth 52 to swing down below tooth 36 to be engaged thereby as soon as the tabulator rocker frame 32 swings back to normal position under the influence of its usual returning spring 53, of my prior patent and the well known Underwood structure, thus engaging the latch lock members together, as shown in dotted line position Fig. 2.

I will now describe the unlocking means for the latch lock. Since the forward and then backward movement of the tabulator rocker frame, as above described, serves to lock the latch lock, it is obvious that a repeated forward swinging movement of the tabulator rocker frame will also serve to unlock the latch lock, by withdrawing the tooth 36 out of tooth 52 as shown in Fig. 3. The means for swinging the rocker frame forward to unlock the latch lock, are the tabulator key 27 and the connections therefrom to the rocker frame. These include the key lever 28, pull bar 29 and the rocker arm 30 fastened to the rocker frame. The pin (54) and slot (55) between the key lever 28 and the pull bar 29 permit the tabulator rocker frame to be swung forward during the locking movement without depression of the key 27.

An advantage of my present structure over my prior patent resides in the ease with which the carriage can be lifted and locked in its lifted position and lowered therefrom and further in that the lock, while retaining all the ease of locking and unlocking, may be made as positive a lock as may be desired and not a mere frictional lock. The locking teeth in my herein device may be made radial to the swinging movement, so as to lock positively, or even under cut for a still more positive locking, or they may be so inclined as that they can be disengaged by a strong pull on the lifted carriage, as well as by the operation of a release

key, as may be desired. But in all cases in my present device the ease of the carriage locking is retained in strong contrast to the hard action with my former friction lock.

I have shown the release key as located in the key board (tabulator key 27). This is because the tabulator key and train of connections to the rocking tabulator mechanism and the convenient rod 37 are already in the Underwood type of machine and I intend applying to such machines now in use, but in the broader claims I do not intend limiting the location of the release key to any particular part of the machine, but intend it may be in the machine body or on the carriage.

I have also provided herein new and improved locking means for preventing endwise movement of the carriage under the influence of the main spring or otherwise, when the carriage is lifted and out of control of the escapement. Such improvement I will now describe. In my said prior patent I have described and claimed a series of three locks to control the carriage, when released from the escapement, throughout its entire lifting movement from normal operative or writing position to its wholly lifted one, and I termed such series in said patent the No. 1, No. 2 and No. 3 locks respectively. The No. 1 lock controlled the initial lift, the No. 2, the intermediate one and the No. 3 the final lifting period. Hence the carriage was continually under locking control during the whole lifting movement. But the three locks were required and even these had to be in very accurate adjustment or the carriage was apt to escape through between the locks for an erroneous endwise feed and that was very bad. This difficulty I have now overcome and in fact, can safely dispense with the intermediate or No. 2 lock of the prior patent, thus greatly simplifying the locking mechanism, particularly when applying the improvement to machines already in use.

In order to make the improvement clear I will explain the mechanism of the former patent which resulted in the need of three very carefully adjusted locks. The reason of the difficulty of the device of the said prior patent was that in that patent the carriage member of the No. 3 lock was mounted on the shaft which forms the pivotal support for the shifting carriage, i. e. the shaft numbered 3 herein. Therefore said member vibrated transversely toward and away from the other member of the lock when the inner carriage was shifted to upper case and lower case positions in the outer carriage. Hence the carriage member had to be set normally a considerable distance forward of the other member so as not to interfere therewith in the upper case position of the inner carriage. This resulted that the No. 1 lock became un-

locked before the carriage member of the No. 3 lock could come into engagement with its mate. Hence the intermediate No. 2 lock was necessary and even then the No. 3 lock did not always become reliably engaged prior to release of the No. 2.

In my present device No. 1 lock is the same as No. 1 lock of the prior patent; No. 2 lock may be dispensed with and the race way member of No. 3 lock is the same in the patent as herein. But the carriage member of the No. 3 lock is different and differently located herein from the one of the prior patent. In my present device the carriage member of lock corresponding to lock No. 3 of the patent is mounted securely on the non-shifting carriage 4, being screwed to the frame thereof, and is numbered 49. The part 49 is therefore non-shifting in the upper and lower case shifting movements of the inner carriage. It has no movement toward or away from the race way member, excepting during the lifting movement of the carriage structure in raising it to lifted nonoperative position. Hence the member 49 may be normally set close up to the race way member 50 in the operative position of the carriage and the parts 49 and 50 become reliably engaged before the carriage has been lifted far enough to disengage the contacts 56 and 57 of the No. 1 lock. Of course the No. 2 lock of the prior patent may still be employed with my present improved device but it is not necessary.

Fig. 9 differs from Fig. 1 in that it shows a wider carriage machine. The mechanism of the Underwood wide carriage machines differ somewhat from the standard width ones but the mechanisms are so well known that no particular detail description is believed necessary, excepting to point out my improvements thereon. These consist of different type of lift locks, shown herein, While the wider machine may employ the same type of restraining lock when released from the escapement, that is one adapted for lifting the carriage at the beginning of the line, or when the carriage is drawn to its extreme limit to the right, still with the wide carriage machines it is preferable to lift the carriage at an intermediate point in its line of travel and in that case a different type of restraining lock is preferable. Fig. 9 shows such lock.

Since the carriage shown in Fig. 9 has two support wheels at the front of the machine, numbered 10^a herein, I provide two slots 44 for the escape of such rollers 10^a, in the upper front locking bar 12^b, corresponding to the predetermined intermediate point at which the carriage is to be lifted, and I mount midway at the rear of the carriage, on the frame of the non-shifting carriage 4, the locking finger 49, by rigidly screwing it on the carriage. Upon the upper race way

rail 15 I rigidly fasten the double restraining arms 50^a and 50^b. The front lock comprises the rollers 10^a and the slots 44 with their right and left hand banking edges 57^a and 57^b; and the rear lock comprises the locking finger 49, with its banking edges 49^a and 49^b, and the restraining arm 50^a with its banking edge 50^a and the restraining arm 50^b with its banking edge 50^b.

The reason for the right and left hand banking stops in Fig. 9 is that the carriage is lifted in an intermediate position. Hence a margin stop can not be conveniently employed and its functions are performed by the right hand banking stops of the lock of Fig. 9.

In the operation of my device, in Fig. 1, I draw the carriage to the right to the limit of its travel, depressing the margin release key 58 in order to pass the margin stop 59. This will bring the carriage pointer 60 slightly to the right of the zero point on the scale, or the graduation where the first letter of writing can begin, the carriage being thus beyond and outside of its normal writing position. When the carriage has been thus moved to its limit to the right with the carriage pointer to the right of the first graduation on scale 61, the margin stop 26^a at the rear of the carriage will bank on the bracket 14, as shown in Fig. 6. The shoe 12^a will also be in the slot 44, so that the carriage will be unlocked and free to be lifted. Then I lift the carriage upwardly and back until the rod 37 engages cam 51 and cams the inner carriage into upper case position in the outer carriage. This brings lock 41 into position to engage the cam face on top of locking member 34 and cams the tabulator rocker frame and locking member 34 thereon forwardly so that the tooth 36 escapes over the tooth 52. Then the spring 53 restores the tabulator rocker frame rearwardly to normal position and the tooth 36 engages in tooth 52 and the carriage is locked up, as above described. When I wish to again lower the carriage I preferably take hold of the carriage to hold it from falling too rapidly when unlocked. Then, with the other hand, I depress release key 27, thus withdrawing tooth 36 forward out of tooth 52 and then lower the carriage to its normal or writing position.

In Fig. 9 to lift the carriage, I simply move it into the position wherein the rollers 10^a are directly in the slots 44, as shown in Fig. 9, and then lift upwardly, the rollers 10^a passing up through the slots 44 and the locking finger 49 swinging down between the double retaining arms 50^a and 50^b. The latch lock is the same in the structure of Fig. 9 as in that of Fig. 1 and therefore the carriage of Fig. 9 locks up and is released in the way already described.

Having thus described my invention, what

I claim and desire to secure by Letters Patent is as follows:

1. In a typewriting machine, in combination, a carriage normally in writing position, said carriage being adapted to be moved to a non-writing position and when so moved to be locked and key operated means to unlock the lock. 70
2. In a typewriting machine, in combination, a carriage normally in writing position, said carriage being adapted to be moved to a non-writing position and when so moved to be automatically locked and a release key in the key board and means operated thereby to unlock the lock. 75
3. In a typewriting machine, a carriage structure which is adapted to be pivotally swung upward from its normal operating position, said carriage structure comprising an inner shifting carriage and an outer non-shifting carriage, means for moving the shifting carriage to upper case position in the outer carriage during said swinging movement, a latch lock to hold the carriage structure in its raised position and key operated means to unlock the latch lock. 80
4. In a typewriting machine, a carriage structure which is adapted to be pivotally swung upward from its normal operating position, said carriage structure comprising an inner shifting carriage and an outer non-shifting carriage, means for automatically moving the shifting carriage to upper case position in the outer carriage during said swinging movement, a latch lock to hold the carriage structure in its raised position, and a key board and a release key therein and means operated by the key to unlock the latch lock. 85
5. In a typewriting machine, a carriage structure which is adapted to be pivotally swung upward from its normal operating position, said carriage structure comprising an inner shifting carriage and an outer non-shifting one, means for moving the shifting carriage to upper case position in the outer carriage during said swinging movement, and a latch lock independent of said means to hold the carriage structure in its raised position. 90
6. In a typewriting machine, in combination, a traveling platen carriage movable about a horizontal pivot whereby it is adapted to be swung out of its normal writing position into an abnormal non-writing one, means for locking the carriage in its non-writing position and a release key and means operated thereby to unlock the carriage from its said non-writing position. 95
7. In a typewriting machine, in combination, a carriage, carriage propelling power and an escapement to normally control the carriage, said carriage being adapted to be moved to a non-writing position and when so moved to be released from the escape- 100
- ment, locking means brought into operation by said movement of the carriage to lock the carriage and to control it against movement under the influence of the propelling power and a key and means operated thereby to release the carriage from its locked position. 105
8. In a typewriting machine, in combination, a carriage, a carriage main spring and an escapement to normally control the carriage, means for normally locking the carriage in its writing position, said carriage being adapted to be moved to a non-writing position at a predetermined point and when so moved to be released from the escapement, locking means brought into operation by the said movement of the carriage to lock the carriage and to control it against movement under the influence of the main spring and a key and means operated thereby to release the carriage from its said locked position. 110
9. In a typewriting machine, in combination with a carriage structure of the visible type, a truck at the rear of the machine to form a travelling support for the carriage, a pivotal connection intermediate the truck and the carriage whereby the carriage may be pivotally swung about the truck to a non-writing position, means for locking the carriage in said non-writing position and a key and means operated thereby to unlock the carriage from said position. 115
10. In a front strike typewriting machine, a carriage structure having a pivot mounting at the rear thereof to permit the carriage to be swung upwardly from its normal operating position on the front guide rail, a lock to maintain the carriage in elevated position, said carriage when in said elevated position tending to swing downwardly to writing position under the influence of gravity and said lock being adapted to prevent said swinging movement and a key and means operated thereby to unlock the lock and release the lifted carriage. 120
11. In a front strike typewriting machine, in combination, a carriage structure which is adapted to be swung upwardly about a pivot at the rear thereof and which is adapted to cooperate with the usual guide and locking rails at the front of the machine when in normal position, locking means to prevent an endwise movement of the carriage under the influence of the motor spring when the carriage is swung upwardly out of control of the escapement and a latch lock to hold the carriage in its raised position and means to unlock the latch lock. 125
12. In a front strike typewriting machine, in combination, a carriage structure which is adapted to be swung upwardly about a pivot at the rear thereof and which is adapted to cooperate with the usual guide 130

- and locking rails at the front of the machine when in normal position, locking means to prevent an endwise movement of the carriage under the influence of the motor 5 spring when the carriage is swung upwardly out of control of the escapement, a latch lock to hold the carriage in its raised position and a key in the key board and connections from the key to the latch lock to unlock the latch lock. 10
13. In a front strike typewriting machine, in combination, a carriage structure having a pivot mounting at the rear thereof to permit the carriage to be swung upwardly from its normal operating position upon the front guide rail, a plurality of overlapping and successively acting locks, said locks being normally ineffective and becoming effective at different points in the upward swinging 15 of the carriage, a latch lock to hold the carriage in its raised position and a key and connections to unlock the latch lock. 20
14. In a typewriting machine, in combination, a carriage support at the rear of the machine, a carriage structure pivotally mounted thereon and supported at the front on a guide way when in operative position and adapted to be pivotally moved therefrom into an inoperative position and locking 25 means to prevent endwise movement of the carriage when so moved, said locking means comprising a member fixedly mounted on the machine and a member fixedly mounted on the carriage whereby it is held against transverse movement toward and from the said machine member excepting when the carriage structure is being pivotally moved. 30
15. In a front strike typewriter, in combination with a truck and with a front guide rail, a carriage structure adapted to be swung upward from its normal position on the front rail, and locking means to prevent the endwise movement of the carriage during 35 its upward swinging movement, said means comprising a member fixed on the machine and a member fixedly mounted on the carriage whereby it is restrained from transverse movement toward and from the machine member excepting while the carriage structure is being swung about the truck. 40
16. In a typewriting machine, in combination, with a carriage structure which is adapted to swing upwardly about a pivot at the rear from a normal position of rest upon a front guide rail, a lock to prevent endwise movement of the carriage during its initial movement away from the guide rail and a second lock to prevent endwise movement of the carriage after it has passed from control of the first mentioned lock until the completion of its upward swinging movement, said second lock comprising a member fixed on the machine and a member on the 45 50 55 60 65
- carriage normally free of the machine member but adapted to engage therewith and restrained from transverse movement toward and from the machine member excepting while the carriage structure is being swung about the said pivot. 70
17. In a front strike typewriter machine, in combination with a truck, a carriage structure which is adapted to be swung upwardly about a pivot at the rear thereof, and which is adapted to cooperate with the usual guide and locking rails at the front of the machine when in normal position, and locking means to prevent an endwise movement of the carriage under the influence of the motor spring when the carriage is swung upwardly out of control of the escapement, said locking means comprising a member fixed on the machine and a member fixedly mounted on the carriage whereby it is restrained from transverse movement toward and from the machine member excepting while the carriage structure is being swung about the truck. 75 80 85
18. In a typewriting machine, a carriage structure which is adapted to be pivotally swung upward from its normal operating position, said carriage structure comprising an inner shifting carriage and an outer non-shifting carriage, locking means for retaining said carriage structure in elevated position, said locking means being adapted to prevent the shifting of the inner carriage in the outer carriage when in elevated locked position and locking means to prevent endwise movement of the carriage structure while being lifted to its elevated position, said last mentioned means comprising a member fixed on the machine and a member fixedly mounted on the non-shifting carriage. 90 95 100 105
19. In a typewriting machine, a carriage structure which is adapted to be pivotally swung upward from its normal operating position, said carriage structure comprising an inner shifting carriage and an outer non-shifting carriage, and means to prevent endwise movement of the carriage structure while it is being swung upward, said means comprising a locking member fixed on the machine and a carriage member normally free of said fixed member but adapted to engage therewith during the upward swinging movement of the carriage, the said carriage member being rigidly fixed on the non-shifting carriage. 110 115 120
20. In a typewriting machine, in combination, a carriage structure adapted to be pivotally swung upwardly from its normal operating position, said carriage structure comprising an inner shifting carriage and an outer non-shifting carriage, and locking means for retaining the carriage structure in elevated position, said locking means being adapted to lift the inner carriage from 125 130

lower case position to upper case position and thereafter lock both inner and outer carriages against relative movement, and means to prevent endwise movement of the carriage structure while it is being swung upward, said means comprising a locking member fixed on the machine and a carriage member normally free of said fixed member but adapted to engage therewith during the upward swinging movement of the carriage, the said carriage member being rigidly fixed on the non-shifting carriage.

21. In a front-strike typewriting machine, the combination of a carriage structure which is adapted to be swung pivotally upward from its operating position into a lifted one, means to limit the extreme upward movement of the carriage whereby the carriage normally tends to fall by gravity toward operating position, locking means to retain the carriage in elevated position against the influence of gravity and means to prevent the endwise movement of the carriage structure while it is being swung upward, said means comprising a locking member fixed on the machine and a carriage member normally free of the said fixed member but adapted to engage therewith during the upward swinging movement of the carriage structure, the said carriage member being rigidly fixed on the non-shifting carriage.

22. In a typewriting machine, in combination, a carriage, carriage propelling power and an escapement to normally control the carriage, said carriage being adapted to be moved to a non-writing position and when so moved to be released from the escapement and locking means brought into operation by moving the carriage to the last named position to control the carriage against movement under the influence of the propelling power while the carriage is out of control of the escapement, said means comprising a member fixed on the machine and a member fixedly mounted on the carriage whereby it is restrained against transverse movement toward the said machine member excepting upon the said movement of the carriage to the non-writing position.

23. In a typewriting machine, in combination, a travelling carriage pivotally supported at the rear, mounted at the front on a guide way and normally controlled thereon against pivotal movement by a locking bar, one or more forwardly projecting parts on the carriage which underlie the locking bar, a recess in the locking bar for the escape of each projecting part and so positioned as to permit of the swinging movement of the carriage on its pivotal support at an intermediate point in its line of travel and locking means at the rear of the carriage having banking stops to prevent lateral movement of the carriage in both

directions, when the carriage is swung to non-writing position.

24. In a typewriting machine, in combination, a travelling carriage pivotally supported at the rear, mounted at the front on a guide way and normally controlled thereon against pivotal movement by a locking bar, a forwardly projecting carriage support wheel running on the guide way and underlying the locking bar, a recess in the locking bar for the escape of said support wheel to permit of the swinging movement of the carriage to a non-writing position and locking means at the rear of the carriage, normally disengaged but adapted to engage together prior to the full escape of the support wheel from said recess to prevent lateral movement of the carriage during its said swinging movement.

25. In a typewriting machine, in combination, a travelling carriage pivotally supported at the rear, mounted at the front on a guide way and normally controlled thereon against pivotal movement by a locking bar, a forwardly projecting carriage support wheel running on the guide way and underlying the locking bar, a recess in the locking bar for the escape of said support wheel to permit of the swinging movement of the carriage to a non-writing position at an intermediate point in its line of travel and locking means at the rear of the carriage, normally disengaged but adapted to engage together prior to the full escape of the support wheel from said recess to prevent lateral movement of the carriage in both directions during its said swinging movement.

26. In a typewriting machine, in combination, a travelling carriage pivoted on a truck at the rear, mounted at the front on a guide way and normally controlled thereon against pivotal movement by a locking bar, a forwardly projecting part on the carriage underlying the locking bar, a recess in the locking bar for the escape of said part to permit the swinging movement of the carriage to a non-writing position at an intermediate point in its line of travel and locking means at the rear of the carriage comprising male and female members, one on the carriage and the other on the truck, normally disengaged but adapted to engage together prior to the full escape of the said part from said recess, to prevent lateral movement of the carriage in both directions during its said swinging movement.

27. In a typewriting machine, in combination, a travelling carriage pivoted on a truck at the rear, mounted at the front on a guide way and normally controlled thereon against pivotal movement by a locking bar, a forwardly projecting carriage support wheel running on the guide way and underlying the locking bar, a recess in the locking bar for the escape of said wheel to permit

the swinging movement of the carriage to a non-writing position at an intermediate point in its line of travel and locking means at the rear of the carriage comprising male and female members, one on the carriage and the other on the truck, normally disengaged but adapted to engage together prior to the full escape of the said wheel from said recess, to prevent lateral movement of

the carriage in both directions during its 10 said swinging movement, the lips of the female member being flaring to insure of the engagement of the male member therein as the circular wheel escapes from the recess.

Signed by me at Tottenville, New York, 15 this 9th day of March, 1922.

FREDERIC W. HILLARD.
